UNITED STATES PATENT OFFICE.

CLARENCE MAYER, OF CHICAGO, ILLINOIS.

GIRDLE BRASSIÈRE.

Application filed March 17, 1922. Serial No. 544,454.

To all whom it may concern:

Be it known that CLARENCE MAYER, a citizen of the United States, and a resident of the city of Chicago, county of Cook, State of Illinois, has invented an Improvement in Girdle Brassières, of which the following is a specification.

This invention relates to garments such as girdle-brassières and the like.

10 Among other objects, the invention is intended to provide a novel and improved garment of this character which may be easily applied and comfortably worn.

The invention consists in the novel combination, constructions and arrangements, hereinafter described or claimed, for carrying out the above stated objects and such other objects as will hereinafter appear.

The invention may be best understood by reference to one illustrative garment embodying the invention and shown in the accompanying drawings.

In said drawings:

Fig. 1 is a perspective view of the garment as it is worn.

Fig. 2 is a perspective view of the back of the garment.

Fig. 3 is a plan or development of the garment.

30 The illustrative garment comprises in general a girdle portion and a brassière portion or equivalent garment, such as a bandeau, made either of one piece of fabric or several pieces suitably secured together.

35 In the illustrative garment 10 designates a girdle formed of suitable fabric and 11 a brassière suitably attached thereto, each preferably consisting of a suitably decorated fabric such as is generally employed in garments of this character.

The girdle comprises a front or abdominal portion 12 and a back portion 13 connected together by elastic webbing 14, such as that known as surgical elastic arranged to fall over the hips. The front portion is provided, if desired, with suitable boning. In the arrangement shown the boning comprises a series of spaced bones 15 secured to the fabric in a herring-bone pattern with the apices pointing down. This arrangement permits considerable freedom of movement on the part of the wearer, particularly providing flexibility along diagonal lines corresponding with the lines of flexure of the body without impairing the efficiency of the boning. If desired the back portion 13

of the girdle may be provided with suitable boning 16.

Suitable hose supports 17 depend from the front and back portions of the girdle and co-operate to maintain the garment properly on the figure.

The brassière comprises front and back portions 18 and 19 attached to the girdle and connected together at one side by a strip 65 of elastic webbing 20 such as surgical elastic. The front portion 18 is suitably tucked as shown at 21 to give the front portion the required fullness to cover the bust. A drawstring 22 along the upper edge is provided 70 for removing any looseness at the top edge of the brassière. Shoulder straps 23 are provided for passing over the shoulders of the wearer and provided with suitable means for permitting adjustment. Such means may 75 comprise a series of button holes 24 arranged to be buttoned over a button on the tabs 25 to secure the required fit. Preferably the tabs 25 are formed of suitable elastic to permit the shoulder straps to yield when necessary. The free edges 26 and 27 of the garment are suitably bound with tape and provided with suitable independent fastening means such as a series of hooks and eyes, thereby preserving the flexibility of the garment at the side.

By arranging the fastening means at the side of the wearer instead of at the front or back, they are accessibly located without causing an uncomfortable and relatively inflexible region at the front of the garment which detracts from the shapeliness of the fit and interferes with the movements of the wearer. Furthermore, in fastening the garment along the side, the flesh of the wearer 95 is smoothed and flattened in front and not crowded together as frequently happens in applying a front fastening garment. The normal contour of the figure at the front is preserved by the fabric front portion of the 100 girdle which, as is clearly shown in the drawings, is without elastic webbing.

Preferably the girdle is provided with elastic webbing 28 and 29 arranged to fall opposite the side at which the webbing 14 falls. Also the brassière is preferably provided with elastic webbing 30 corresponding with the webbing 20 at the opposite side of the garment. This elastic webbing holds the garment snugly about the wearer while providing the required elasticity to permit freedom of movement.

2
While for the sake of brevity in describing the invention, I have employed the terms "brassière" and "girdle" in the sense in which these terms are understood in the 5 trade, it is intended to include under these terms functionally equivalent garments.

Obviously the present invention is not limited to any particular form of construction and the details of the illustrative garment 10 may be variously modified. Moreover it is not indispensable that all features of the invention be used conjointly as they may be advantageously employed in various combinations and sub-combinations.

15 Claims:

1. A garment comprising a girdle constructed and arranged to encircle the figure from the waist downwardly over the hips; said girdle comprising fabric front and 20 back portions to cover respectively the abdominal and back portions of the figure, and elastic webbing hip-covering portions at the sides secured to said front and back portions respectively and constructed and 25 arranged to conform to the contour of the figure at the hips; one of said elastic webbing portions being divided longitudinally and having cooperating fastening means along its adjacent edges for securing the 30 girdle about the figure.

2. A closed front girdle constructed and arranged to encircle the figure in the region of the hips comprising, in combination, a closed fabric front portion and a fabric 35 back portion for covering, respectively, the abdominal and back portions of the figure, and elastic webbing hip-covering portions extending from the top to the bottom of the girdle at the sides and constructed and 40 arranged to conform to the contour of the hips; said girdle constructed and arranged to open at the side; the elastic webbing at that side being provided at its securing edge with a series of independent fastening 45 elements; the other edge of the open side being provided with a series of independent fastening elements; the elements in each series directly cooperating with the elements in the other series to secure the girdle 50 about the figure, thereby preserving the flexibility of the girdle at that side.

3. A garment comprising in combination a girdle constructed and arranged to encircle the figure in the region of the hips;

said girdle comprising fabric front and 55 back portions for covering respectively the abdominal and back portions of the figure, and elastic webbing hip-covering portions extending from the top to the bottom of the girdle at the sides and constructed and 60 arranged to conform to the contour of the hips; said fabric front portion provided with series of spaced boning to stiffen said front portion and arranged to permit maximum flexibility of said front portion in use 65 along lines converging downwardly towards the vertical center line of the front portion and hose supporters extending from the lower edge of said girdle and cooperating in use with said elastic webbing and 70 said boning to maintain the conformation of said girdle to the contour of the figure.

4. As an article of manufacture, a girdle-brassière of the type described comprising a brassière portion and a hip encircling 75 girdle portion each having elastic webbing at the sides thereof; the webbing of the girdle portion being in alignment with the webbing of the brassière portion; said webbing of the girdle covering and conforming 80 to the contour of the hips; said garment being open at one side and having independent fastening means at that side for securing the garment about the figure and preserving 85 the flexibility of the garment at that side; said girdle having a series of spaced bones arranged in a herring-bone pattern down the front thereof with the apices of the bones pointing down, thereby 90 providing flexibility but preventing undesirable bulging.

5. A garment of the class described comprising a closed front girdle portion and a brassière portion each made of the usual fabric and each having elastic webbing at 95 the sides thereof; the elastic webbing in said girdle being arranged to cover and conform to the hips; said garment being open throughout its length at one side and having separate hooks and eyes secured thereto adjacent the edges to fasten the garment about the figure; the fabric front of 100 said garment preventing any substantial bulging or contraction of the figure at the front.

In testimony whereof, I have signed my name to this specification.

CLARENCE MAYER.
